(57) **CLAIM**

The ornamental design for a carrying case, as shown and described.

DESCRIPTION

FIG. 1 is a front elevational view of the carrying case;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, left-side, top perspective view thereof; and,

FIG. 8 is a rear, right-side, top perspective view thereof.

The broken lines illustrate portions of the carrying case that form no part of the claimed design.
